(57) **CLAIM**

The ornamental design for ventilation fan, as shown and described.

DESCRIPTION

FIG. 1 is a perspective view according to our new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a top plan view thereof;
FIG. 7 is a bottom plan view thereof;
FIG. 8 is a cross-sectional view taken along line 8-8 of FIG. 1;
and,
FIG. 9 is an exploded perspective view of our new design
shown in FIG. 1.
The broken lines shown in figures illustrate environmental
structures and form no part of the claimed design.
